UNITED STATES PATENT OFFICE.

WILLIAM BAYLEY, OF SPRINGFIELD, OHIO, ASSIGNOR TO THE TORONTO REAPER AND MOWER COMPANY, OF SAME PLACE.

MOWING-MACHINE.

SPECIFICATION forming part of Letters Patent No. 392,658, dated November 13, 1888.

Application filed January 3, 1887. Serial No. 223,179. (No model.)

To all whom it may concern:

Be it known that I, WILLIAM BAYLEY, of Springfield, in the county of Clark and State of Ohio, have invented a new and Improved 5 Mowing-Machine, of which the following is such a full, clear, and exact description as will enable any person skilled in the art to which it applies to construct and use the same, reference being had to the accompanying drawings, forming a part of this specification.

My invention relates to mowing-machines in general and particularly to that class of machines commonly known as "two-wheeled chain-drive-gear machines," and is in the nature of improvements upon the usual form, arrangement, and construction of such machines.

The objects of my invention are to so construct a mowing-machine that by peculiarly-jointed connections the cutting apparatus may be raised to a vertical position, the inner end thereof rise and fall, the outer end rise and fall, the points of the fingers or guards tilt up or down to follow the undulations of the ground over which it passes, all these operations being accomplished while the machine is running. These objects are successfully accomplished by means of the devices hereinafter described, and illustrated in the drawings hereunto attached.

In the drawings, Figure 1 is a side elevation of the complete machine. Fig. 2 is a plan of the machine, omitting the elevating and tilting levers. Fig. 3 is a vertical section 35 through the main shaft, main frame, and master-wheels, showing the device for throwing the machine into and out of gear. Fig. 4 is a side elevation, and Fig. 5 is an end elevation, of the shipping-lever by which the machine is 40 thrown into and out of gear. Fig. 6 is a partial side elevation showing the device for tilting the cutting apparatus. Fig. 7 is a partial side elevation showing the device for raising and lowering the inner end of the cutting apparatus. Fig. 8 is a partial side elevation 45 showing the device for elevating and depressing the outer end of the cutting apparatus. Fig. 9 is a cross-section through the draft-tongue and sliding whiffletree-bracket. Fig. 50 10 is a perspective view of the inner shoe and the bracket to which it is pivoted. Fig. 11

is a perspective view of the combined bevel gear-wheel and sprocket-pinion, the crank-shaft, and bevel-pinion, &c., showing the method of journaling the bevel gear-wheel on the diagonal brace and its relation to the crank-shaft. Fig. 12 is a vertical longitudinal section of the gear-case, shoe-bracket, shoe, &c., on a line with the crank-shaft. Fig. 13 is a horizontal section of the combined bevel-gear 60 and sprocket-pinion, bevel-pinion, crank-shaft, gear-case, &c., on a line with the crank-shaft. Fig. 14 is a perspective view of the supporting-bar. Fig. 15 is a perspective view of the drag-bar; and Fig. 16 is a side elevation 65 of the sprocket-wheel, sprocket-pinion, and chain-tightening device.

Similar letters refer to like parts in the several views.

A is the main frame, consisting of a long 70 "pipe box" or tube of cast metal, through which the main shaft b passes loosely. At the rear side of the frame A and near its center is formed the seat-spring bracket a, to which is attached the seat-spring a², supporting the driver's seat A³. At the front side of the main frame and near one end is formed the lug or ear a⁴, to which is pivoted the supporting-bar C, and another lug, a⁴, to which is pivoted the diagonal brace D, while the draft-tongue 75 T is fixed to the bracket a⁵, also formed on the front side of the main frame A. Upon the outer ends of the main shaft b are pivoted or journaled the main driving and supporting wheels B and B², which are provided with the 80 backing-ratchets b², which, during the forward movement of the machine, are engaged by the usual pawls, b³, pivoted in the plates b⁴ and b⁵, fixed to the main shaft in the usual manner.

Loosely fitted upon the main shaft is the 85 sprocket-wheel E, upon one end of whose hub is formed the half-clutch e, which engages the half-clutch e² on the backing ratchet-plate b⁴, as hereinafter described. A portion of the hub of the sprocket-wheel E is recessed in the 90 form of a sleeve and fits over a portion of the pipe-box of the main frame A, which has a groove formed in it, the sprocket-wheel E being held in place by the pin e³ in the sprocket-wheel E, which enters said groove, 95 as shown in Fig. 3.

Upon the backing ratchet-plate b⁵ is formed

a sleeve over which is fitted the shipper-lever F, a collar, b⁶, formed on the plate b⁵, engaging an inwardly-projecting rim, f, formed on the lever F, preventing lateral motion of the latter in relation to the plate b⁵. Formed in the lever F is the cam-slot f², which is engaged by the hook f³, which is fixed to the main frame by passing through a lug, a⁶, formed thereon. The relative position, therefore, of the main frame to the plate b⁵ is controlled by the shipper-lever F, and as the sprocket-wheel E is carried by the main frame independent of the main shaft or the backing-plate b⁴ and its half-clutch e², it follows that by swinging the shipper-lever F back or forward the main frame and sprocket-wheel E will be moved laterally to the position shown by dotted lines in Fig. 3 and the machine thrown into and out of gear—i. e., started and stopped—as may be desired, the spring-pin f⁴ in the shipper F engaging slight slots (not shown) in the main frame to hold the shipper in either position.

The lateral movement of the sprocket-wheel E in the act of being thrown into and out of gear is not sufficient to disturb the working relation of the drive-chain.

G is a casting forming a casing for the combined bevel-gear and sprocket-pinion J and bevel-pinion K, as well as a bracket to which the inner shoe, H, of the cutting apparatus is pivoted, and has formed upon it the projection g, to which is fixed the drag-bar L, and also proper journals for the crank-shaft M.

The diagonal brace D is pivoted to the main frame at a⁴, and projects diagonally downward and forward to the gear-casing G, where it is bent at such an angle as to make it parallel to the main shaft b. At this point it is circular, and, passing through the supporting-bar C at c, Fig. 14, and the drag-bar L at l, Fig. 15, it forms a pivot or journal, upon which the bevel-gear and sprocket-pinion J revolves, after which it passes through the gear-casing G, and is perforated for the passage of the crank-shaft M, and confined to its place by a nut placed outside of the gear-casing G. The form, position, and relation of these parts are shown in detail in Figs. 11, 12, and 13, and in general in Figs. 1 and 2.

The supporting-bar C is pivoted to the main frame at a³ and projects forward and downward at right angles to the main shaft b, and is pivoted at c to the diagonal brace D, as described, the pivots at a³ and a⁴ serving to pivotally connect the cutting apparatus and its appendages to the main frame, by which the former may be free to rise and fall with respect to the latter.

It is obvious that the diagonal brace D and the supporting-bar C should, strictly speaking, be pivoted upon or around the main shaft b or the pipe-box of the main frame A, in order that the sprocket-pinion J may always maintain its proper position in relation to the large sprocket-wheel E on the main shaft; but by pivoting the diagonal brace D and supporting-bar C to the ears a³ and a⁴, which centers

or pivots are directly in line with the main shaft b and sprocket-pinion J and quite near the main shaft, their positions are changed so slightly when the cutting apparatus is elevated and depressed that practically their working relations are not impaired.

The drag-bar L is fixed to the gear-casing G by bolts at g², g³, and g⁴, being braced by the brace-rod g⁵, and at its front end pivoted to the tilting-lever N, which in turn is pivoted to the whiffletree frame or plate Q, to which the whiffletrees are pivoted at d, which slides upon the track P, fixed to the draft-tongue, as shown in Figs. 1 and 2. By this device the cutting apparatus is “tilted”—i. e., the points of the fingers elevated or depressed (turning on the diagonal brace where it passes through the bevel-gear as a center) by means of the tilting-lever N, which is held in any desired position by the latch n engaging properly-formed depressions or notches in the segment-plate q¹, forming part of the whiffletree-plate Q. This operation and the relation of the parts in several positions are clearly shown in Fig. 6.

To the draft-tongue T is pivoted the foot-lever O, having a properly-formed foot-piece at the top and the bottom end extended beyond its pivotal point and being connected to the supporting-bar C by the link g. By this device the operator may with his foot press upon the top end of the foot-lever O and elevate the inner end of the cutting apparatus, as shown in Fig. 7, the whiffletree-frame Q sliding upon the track P as necessary, and the catch-lever q², pivoted to the draft-tongue, serving to hold the foot-lever O whenever desired, the spring q³ throwing the catch-lever q² forward, so as to engage the foot-lever O when ever it is depressed.

The inner shoe of the cutting apparatus is pivoted to the gear-case G by sleeve g⁶, formed upon the rear end thereof, and by a simple pivoted joint at h, the said joints being in the line with the crank-shaft. By this construction the vertical swinging of the cutting apparatus on the joints g⁶ and h does not disturb the working relation of the crank-shaft M and flywheel m.

The outer end of the cutting apparatus is elevated by the elevating-lever R, which is pivoted to a stud formed upon the gear-casing G, and having the right-angled projection r, which is pivotally connected with the inner shoe by the link-rod S, the elevating-lever R being held in place by the usual catch-pin, r², engaging proper projections formed upon the segment U, which is formed upon the gear-casing G. The operation of elevating is shown in Fig. 8, wherein the elevated position of the cutting apparatus is shown by dotted lines.

The cutting apparatus is driven by a drive-chain, e¹, passing over and around the sprocket-wheel E and sprocket-pinion J', attached to the bevel-pinion J, which engages and drives the bevel-pinion K, fixed to the crank-shaft M, upon which is also fixed the

usual crank-wheel, *m*, from whose wrist the pitman *V* is connected to the cutter-bar *W*, sliding upon the finger-bar *X*, in the usual manner.

5 The drive-chain *e*⁵ is tightened by the idle-pulley *Y*, pivoted upon the lever *Y*², which is pivoted at its lower end upon the diagonal brace *D*, and is secured in any desired position by the bolt *y*, passing through the slot in a 10 curved projection on the lever *Y*² and into the gear-casing *G*.

Having thus described the construction, arrangement, and operation of my machine, and pointed out its new and useful features, what 15 I claim as new, and desire to secure by Letters Patent, is—

1. In a cutting apparatus for a harvesting-machine, a crank-shaft, and a driving-gear in engagement therewith located upon and above 20 the inner shoe of said cutting apparatus, combined with a lateral coupling arm or brace pivoted to said shoe on an axis coincident with the center of said gear, whereby the points of the cutters and guards may be tilted on an 25 axis coincident with the axis of the driving-gear, substantially as set forth.

2. In a harvesting-machine, the combination of a rigid drag-bar fixed at its rear end to the bracket to which the inner shoe is pivoted and at its front end pivoted by a suitable 30 movable connection to a whiffletree-bracket, sliding upon the draft-tongue or some fixed part thereof, a diagonal brace pivoted at its front end to the bracket to which the inner shoe is pivoted, and a supporting-bar pivoted at its rear end to the main frame and at its front end to the bracket to which the inner shoe is pivoted, in combination with a cutting 35 apparatus, substantially in the manner shown 40 and described, and for the purpose of enabling

the cutting apparatus to freely follow the undulations of the ground over which it passes, and by suitable connecting parts to be under complete control of the operator to raise the inner end of the cutting apparatus independent of the outer end, or the outer end independent of the inner end, and at the same time to enable the cutting apparatus to be rocked or rolled in the line of its length. 45

3. In a harvesting-machine, a whiffletree 50 bracket or plate adapted to slide upon the tongue or some fixed part thereof and having pivoted to it a whiffletree and a tilting-lever, to which in turn is pivoted the front end of the drag-bar, substantially in the manner 55 shown and described, and for the purpose of forming a direct connection between the whiffletree and cutting apparatus, and at the same time to allow the latter to be tilted up or down, as may be desired. 60

4. In a harvesting-machine, the combination of a whiffletree-plate sliding on the draft-tongue or some fixed part thereof, a drag-bar pivotally attached at its front end to said whiffletree-plate, the rear end of said drag-bar 65 being fixed to the bracket to which the cutting apparatus is pivoted, and a diagonal brace and a supporting-bar, each of which is pivoted at its rear end to the main frame and at its front end to the bracket to which the cutting apparatus 70 is pivoted, substantially as shown and described, and for the purpose of flexibly connecting the cutting apparatus with the main frame, yet with the proper degree of rigidity to withstand the usual strains to which it is 75 subjected.

WILLIAM BAYLEY.
